UNITED STATES PATENT OFFICE.

ALBERT EDWARD WELLS, OF PITTSFIELD, MASSACHUSETTS, ASSIGNOR OF ONE-HALF TO CHAUNCEY A. CORNELL AND WILLIAM J. BAUGHMAN, OF SAME PLACE.

ELECTRIC SWITCH.

SPECIFICATION forming part of Letters Patent No. 632,076, dated August 29, 1899.

Application filed February 7, 1898. Serial No. 669,378. (No model.)

To all whom it may concern:

Be it known that I, ALBERT EDWARD WELLS, of Pittsfield, in the county of Berkshire and State of Massachusetts, have invented a new and Improved Electric Switch, of which the following is a full, clear, and exact description.

The object of the invention is to provide a new and improved electric switch for use on switchboards in electric light, power, or other plants or places and which is simple and durable in construction, not liable to get out of order, positive in its action, and of a large capacity, and arranged to insure a simultaneous breaking of all points in a circuit, the arcing being reduced to a minimum.

The invention consists of novel features and parts and combinations of the same, as will be hereinafter fully described, and pointed out in the claims.

Reference is to be had to the accompanying drawings, forming a part of this specification, in which similar characters of reference indicate corresponding parts in all the figures.

Figure 1 is a face view of the improvement arranged for a two-pole double-throw switch. Fig. 2 is a transverse section of the same on the line 2 2 of Fig. 1. Fig. 3 is a similar view of the same on the line 3 3 of Fig. 1. Fig. 4 is a sectional plan view of the same on the line 4 4 of Fig. 1. Fig. 5 is an enlarged sectional side elevation of one of the shutter-boxes on a terminal block, the section being taken on the line 5 5 of Fig. 6. Fig. 6 is a sectional plan view of the same on the line 6 6 of Fig. 5. Fig. 7 is an inner face view of one of the shutter-box covers, and Fig. 8 is an enlarged perspective view of one of the shutters.

The switch is mounted on a suitably-constructed board or slab A, of wood, marble, or other material, and on one face of the said board is secured a guideway B, in which is fitted to slide a slide C, provided at or near its middle with a friction-roller C', engaging a slot D', formed in one end of a lever D, fulcrumed at D' on the guideway B, and extending through an opening A' to the other face of the switchboard, as is plainly indicated in the drawings. On this end of the lever D is

secured a handle D'' under the control of the operator for throwing the slide C into a lowermost, uppermost, or intermediate position to break and make contacts, as hereinafter more fully described. A friction-roller E, 55 journaled on a spring-pressed rod held to slide on the lever D, travels on the peripheral surface of a segment E', secured to the rear face of the board A, said friction-roller being adapted to drop into a notch E'', formed on the segment, to hold the lever D in a middle position, the switch-plates being completely out of contact, as hereinafter more fully described.

The slide C is provided with transversely-extending bars C'' of hard rubber or other suitable material, and on the outer ends of said bars are secured arms C''', on the ends of which are removably secured by bolts or other means the contact-plates F F' F'' F''', made of copper or other suitable material, the same as the 70 arms C'''. The contact-plates F F' F'' F''' are adapted to make contact with pairs of contact-plates G, attached to the terminal blocks H H' H'' H''' H'''' H''''' H'', fastened by bolts or other devices to the board A, and with the contact-plates G and a portion of the blocks enclosed in shutter-boxes I, each made of rubber or other insulating material and secured by insulating-screws J to the terminal blocks, 75 as will be readily understood by reference to Fig. 6.

Each box I is provided with a removable cover I', fastened by screws to the box, and in one side of the box is formed a slot I'', registering with a slot I''' in the corresponding 85 cover, said slots permitting the corresponding contact-plate F, F', F'', or F''' to pass within the box to make contact with the contact-plate G contained in the box.

As illustrated in Fig. 1, the two uppermost 90 contact-plates F F'' of the slide are adapted to make contact with the contact-plate G on the terminal blocks H H' and H'' H''', and the lowermost plates F' F''' are adapted to make contact with the contact-plates G on the terminal blocks H'' H''' and H'''' H''''. As shown in the drawings the lever D is in an uppermost position, the slide C being in a lowermost position and with the contact-plates F F'' in engagement with the contact-plates of the ter- 95 100

5 minal blocks H^3 H^3 and with the contact-
plates $F' F^3$ in contact with the contact-plates
 G on the terminal blocks H^4 H^5 . Now when
the lever D is moved downward into a cen-
tral position with the friction-roller E in en-
gagement with the notch E^2 then an upward
sliding motion is given to the slide C to move
the several contact-plates $F F^2$ and $F' F^3$ out
10 of engagement with their contact-plates and
completely out of the boxes I to stand inter-
mediate of adjacent boxes. A further down-
ward movement in the direction of the arrow
 a' brings the lever D into a lowermost position
15 and the slide C into an uppermost position,
so that the contact-plates $F F^2$ make contact
with the plates G for the terminal blocks $H H'$,
and the other plates $F' F^3$ make contact with
the plates G for the terminal blocks H^6 and H^7 .
The slots I^2 and I^3 in each box and its cover
20 are instantly closed on a contact-plate $F, F',$
 F^2 , or F^3 leaving its corresponding box by
means of a shutter K , so that arcing is re-
duced to a minimum, the shutter being ar-
ranged to readily swing open by a contact-
25 plate F, F', F^2 , or F^3 entering a box through
the registering slots. Each shutter K is made
of rubber or other similar insulating material
and is provided with an arm K' and an arm
 K^2 , standing at an angle from the arm K' ,
30 near the free end thereof, said arm K' being
hung on a pivot L , secured to the cover I' , as
is plainly shown in Fig. 7. The inner side
of the cover I' is formed with a recess I^4 for
the reception of said arm K' . A spring N is
35 arranged within the recess I^4 and is secured
at one end by a screw N' to the box-cover, the
free end pressing against the arm K' of the
shutter K , so as to normally hold the latter
in a closed position, as soon as the contact-
40 plate F, F', F^2 , or F^3 is out of the box. The
free end of the arm K' is beveled, as at K^3 , so
that the entering contact-plate strikes this
bevel to swing the shutter to one side into the
position shown in dotted lines in Fig. 7 to al-
45 low the contact-plate to pass into the box and
engage the corresponding pair of contact-
plates G . Now when the contact-plate passes
out of the box on moving the switch-slide C , as
previously explained, then the spring N will

force the shutter to close at once before the 50
extreme outer edge of the contact-plate leaves
the box, and consequently the shutter passes
between the end of the contact-plates F and
 G to prevent arcing, especially as the enter-
ing-slots for the contact-plates F are closed 55
by the shutters.

It will be seen that by the arrangement de-
scribed a simultaneous breaking of the con-
tact takes place when the slide is actuated by
the lever D , as previously explained, and the 60
arcing due to the breaking of the contact is
reduced to a minimum.

The slot D' is of such a length that the fric-
tion-roller C' is at the end of the slot when
the slide has moved into an uppermost or low-
ermost position, so as to prevent a further
movement of the slide and its contact-plates
and injury to the latter and to the terminal
blocks. By having the shutter pivoted on
the removable cover I' of the box I conven-
ient access is had to all parts in the box upon
removing the cover.

Having thus fully described my invention,
I claim as new and desire to secure by Letters
Patent—

1. An electric switch provided with a ter-
minal-block box having a cover with a slot
registering with a slot in one side of the box
proper, and a two-armed shutter within the
box and having one of its arms pivoted on
the inside of the box, the arms of the shutter
being adapted to close said slots, substantially
as shown and described. 75

2. An electric switch provided with a ter-
minal-block box having a cover with a slot
registering with a slot in one side of the box
proper, a two-armed shutter within the box
and having one of its arms pivoted on the in-
side of the box, the arms of the shutter be-
ing adapted to close said slots, and a spring
pressing the shutter to hold the same nor-
mally shut, substantially as shown and de-
scribed. 85
